[57] CLAIM

The ornamental design for a boat, substantially as shown and described.

DESCRIPTION

FIG. 1 is a front elevational view of a boat showing my new design;

FIG. 2 is a rear elevational view thereof;

FIG. 3 is a top plan view thereof;

FIG. 4 is a left side elevational view thereof with the right side being substantially identical;

FIG. 5 is an enlarged perspective view of a portion of the right rear of the boat shown in FIG. 3;

FIG. 6 is a left rear perspective view thereof; and

FIG. 7 is a left front perspective view thereof.

In FIGS. 3 and 5 the close parallel lines represent portions of the deck and cockpit which have been cut out for hatches and the cross hatching represents non-skid surface finish.
